MODULATION SYSTEM

Application filed August 6, 1925. Serial No. 48,435.

My invention relates to radio sending apparatus and particularly to modulation methods for impressing audio-frequency vibrations upon the radiated output.

- 5 An object of my invention is to provide a radio sending apparatus and modulating means therefor, whereby complete modulation of the oscillation generator may be obtained without distortion.
- 10 Another object of my invention is to provide means whereby a modulator triode may be effectively worked at a higher rate of energy input than the associated oscillator.

15 Another object of my invention is to provide a voltage transformation means between an oscillator triode and a modulator triode.

Modulation of the radio frequency output of a triode oscillator system has been commonly obtained by the so-called "constant current" system shown and described 20 in Patent No. 1,442,147 to Heising. This system contains an oscillator triode and a modulator triode the plate circuits of which are connected in parallel and supplied 25 through a "constant current" inductance which holds the total current through the two triodes at a constant steady value. The modulator triode then passes current in proportion to the instantaneous voltage upon its 30 grid and the remainder of the current supplied passes through the oscillator triode. Fluctuations impressed upon the grid of the 35 modulator triode then cause the development of corresponding fluctuations in the voltage impressed upon the oscillator triode and in the amplitude of its oscillations.

This system has been found incapable of 40 providing complete modulation of the output of the oscillator without the introduction of distortion, because the modulator triode current does not follow in strict proportion to the changes in voltage impressed upon its grid when the current values are near the maximum or the minimum value.

45 Under usual operating conditions when no modulation is being effected, the two triodes take integrated amounts of current proportional to the average grid bias as effected by the oscillator.

50 When the modulator triode is operated and

the current in it changed, causing it to take the minimum instantaneous amount of current, it does not take zero current, and the oscillator triode does not take the total current supplied to the system. Likewise, at 55 the other extreme, the modulator triode does not become a perfect conductor and, therefore, the current value through the oscillator is never reduced to zero. Because of this distribution of current in the respective 60 triodes, the voltage upon the oscillator never reaches either zero or twice the supply voltage and therefore complete modulation is not obtained.

In the operation of the conventional systems, the current distribution between the two 65 triodes is not equal. With the same bias upon the grids of the modulator and oscillator triodes, when the grids are biased to the midpoint of the characteristic curves, with 70 the generator triode in oscillation, less than half of the total current is taken by the oscillator and the modulator triode takes more than half. The total energy absorbed by the 75 modulator and available for modulation in the oscillator is therefore more than half of the energy supplied, but since the modulation of the oscillator is controlled by the voltage produced by the modulator no greater 80 modulation is obtained than would be obtained if equal currents were taken by both triodes.

85 My invention provides means comprising a voltage transformation device between the modulator and oscillator triodes whereby advantage is taken of the excess energy absorbed by the modulator triode to obtain more nearly complete modulation of the 90 oscillation generator. By this means, I am enabled to obtain more nearly complete modulation without the production of distortion.

95 Other objects and structural details of my invention will be apparent from the following description when read in connection with the accompanying drawing, wherein,

Fig. 1 is a diagrammatic representation of circuits and apparatus embodying a preferred form of my invention.

Fig. 2 shows curves of the oscillator voltage 100

with and without the device of my invention, and

Fig. 3 is an alternative embodiment of my invention.

5 The first embodiment of my invention provides an oscillation radiating system 1 connected to a local oscillation circuit 2 which is energized by an oscillator triode 3. A modulator triode 4 is provided and the grid circuit 10 thereof is connected through a transformer 5 to a microphone 6 and local battery 7. The cathodes of the triodes 3 and 4 are energized by a current source 8.

An anode current source 9 is provided and 15 its negative terminal is connected to the cathode circuit. The positive terminal of the generator 9 is connected to one terminal of an auto-transformer 11, the other terminal of which is connected to the plate circuit of the 20 triode 3. A tap 10 connects the auto-transformer 11 to the anode of triode 4. The generator 9 is shunted by an audio-frequency condenser 12 connected across its terminals.

If the tap upon the auto-transformer 11 25 were shifted to the terminals to which the oscillator anode circuit is connected the device would correspond to the system in common use and the transformer 11 would function simply as a steadyinductance. Under 30 these conditions, the system would operate in the known manner and the voltage applied to the oscillator triode would correspond to the curve "a" of Fig. 2. This curve which is incomplete, represents the maximum modulation which can be obtained from such system. The curve "a" represents the change in 35 voltage in the conventional systems, with change in grid potential of the modulator both of the modulator anode circuit and the oscillator anode circuit.

40 By positioning the tap upon the auto-transformer coil of the transformer 11 at a point whereby two-thirds to three-fourths of the inductance is included in the modulator circuit and all of the inductance is in the oscillator circuit, a transformer action is obtained.

Under this condition curve "a" of Fig. 2 45 still represents the change in voltage upon the modulator triode but the transformer action of the transformer 11 increases the effective voltage applied to the oscillator 3 to produce a voltage curve corresponding to curve "b" of Fig. 2, which indicates the voltage applied to the oscillator when the voltage change is that of curve "a". By this 55 means, the excess current carrying capacity of the modulator triode over that of the oscillator triode is made to produce greater modulation of the oscillation generator. This system of connections causes the production of a small audio-frequency vibratory current component in the generator circuit, which is by-passed by the condenser 12.

60 65 Similar results may be obtained by the em-

bodiment shown in Fig. 3 in which parts corresponding to those of Fig. 1 bear similar numerals. In this embodiment, the modulator triode 4 is supplied through a separate filter inductance 15 and the audio-frequency component is conveyed to the auto-transformer 14 and the condenser 12. The presence of this audio-frequency component in a portion of the windings of the transformer 14 results in an increased modulation voltage 70 upon the triode 3 in a manner similar to that produced by the embodiment of Fig. 1. 75

80 While I have shown and described but two embodiments of my invention, it is capable of other modifications and it is desired therefore that only such limitations shall be imposed thereon as are imposed by the prior art 85 as indicated in the appended claims.

I claim as my invention:

1. A radio signalling system comprising an 90 oscillation generator tube, a modulator tube, and connecting means therebetween having a voltage ratio other than unity, said modulator tube having a current capacity different 95 from the current capacity of the generator tube by an amount proportional to the voltage ratio of said connecting means.

2. A radio signalling system comprising an 100 oscillation generator tube, a modulator tube of greater current capacity, and electric energy transfer means therebetween having a voltage ratio other than unity the modulator side if said transfer means having the larger current, whereby complete modulation of 105 said oscillator is obtained without such great change of current in said modulator as to depart from the linear portion of its characteristic curve.

3. In a radio transmitting system, a vacuum-tube oscillator, a vacuum-tube modulator, a common source of plate potential for 110 said vacuum tubes, an inductor included between the positive terminal of said potential source and the plate of said oscillator tube, and a connection from the plate of said modulator tube to an intermediate point on said inductor, whereby potential variations across 115 said inductor arising from changes in the impedance of said modulator tube are stepped up and applied to the plate of said oscillator tube.

In testimony whereof, I have hereunto subscribed my name this 11th day of July, 1925.

ROBERT L. DAVIS.
